UNITED STATES PATENT OFFICE.

FRANK F. FOWLE, OF CHICAGO, ILLINOIS.

ELECTRICAL CONDUCTOR.

Application filed July 3, 1924. Serial No. 723,863.

This invention relates to electrical conductors.

One object of my invention is to provide an improved and superior type of composite electrical conductor comprised chiefly of two metals, one for mechanical strength and one for electrical conductivity.

Another object is to provide an improved composite electrical conductor in which the metal for conducting most of the current is encased within a metal of high strength, low magnetic permeability and in which the so-called "skin effect" is reduced to a minimum.

Another object is to provide an improved composite electrical conductor adapted to meet the various requirements under service conditions.

These and other objects are accomplished by means of the arrangements disclosed on the accompanying sheet of drawings, in which—

Figure 1 is a cross sectional view of a seven wire cable, the center wire being of copper and the six outer wires being of steel and each of said wires being zinc-coated.

Figure 2 is a longitudinal view of a piece of such seven-wire cable.

Figure 3 is a cross-sectional view of another cable in which the seven center wires are of copper and are stranded to form a core, and the outer wires of steel comprise two layers in a concentric-lay cable.

Figure 4 is a cross sectional view of another cable, known as a rope-lay cable, in which there are seven main strands placed concentrically and each of these strands in turn consists of seven wires in concentric-lay, the central strand forming a copper core and each of the other strands having a single copper core with a covering of six steel wires.

Figure 5 is a cross-sectional view of a steel-covered copper wire having a protective coating of zinc applied to the outer surface of the steel; preferably the steel and copper are united as by brazing or welding.

Figure 6 is a cross-sectional view of a composite stranded cable in which the center wire is of copper and each of the other wires is a steel-covered copper wire, each of said seven wires being zinc-coated.

Figure 7 is a diagram showing the relationship between carbon content of steel and "skin effect".

While in the description of these figures reference has been made to copper wire or filaments, it will be understood that an aluminum wire or filaments may be used in place thereof and non-corrosive coatings other than zinc may be used; also that many more modifications and arrangements of wires and strands may be made within the spirit of the invention.

As above indicated, in carrying out one embodiment of my invention, I provide a seven-wire cable, as shown in Figure 1, including a central core wire 10 and six wires 11 laid thereon in helical convolutions, or so-called concentric-lay. The six outer wires 11 are made of high-carbon steel and are provided with a coating 12 of zinc for protection against corrosion. The core wire 10 preferably is made of copper and is provided with a coating 13 of zinc to secure further protection from corrosion by having only like metals in actual superficial contact with each other, that is, in this case, zinc in contact with zinc.

Among the advantages of this construction is the mechanical protection of the copper by the surrounding wires of hard, tough steel, which protects the copper from injury in handling or installing the conductor, and particularly these hard steel wires protect hard-drawn copper from accidental surface nicks or scratches which ordinarily cause it to become more susceptible to fracture. Furthermore, the surrounding steel wires completely enclose the copper from the weather and thus tend to prevent electrolytic corrosion of the steel by reason of the contact with the copper and the possible presence of an electrolyte in contact with both metals. However, as above indicated reliance is not placed entirely upon the fact that the steel wires surround and enclose the copper wires, but a protective coating of zinc on the steel wires and a similar coating on the copper wire is employed.

Another advantage is the ability to combine copper and steel elements in one conductor with the use of small ratios of copper to steel without making the outer metal of such small thickness that it lacks good mechanical properties. A copper-covered steel wire of the type which has been used with a small ratio of copper to steel, for example, 30 percent, has a very thin coating of copper,

so thin, in fact, as to lack good mechanical properties and be subject to injury, such as cracks, and abrasions, exposing the steel. The defect is overcome by placing the steel outside of the copper, either in a composite stranded cable or in a composite solid wire. Not only is a superior composite conductor provided by placing the copper wire within the steel, either in the form of a solid composite wire or a composite stranded cable, but a superior composite conductor also is provided assuming the proper kind of steel is used.

I have discovered that to produce a successful composite electrical conductor, it is most essential to employ steel which contains at least as much as .30% content of chemically combined carbon and advantageously more than such amount. In the many experiments which I have conducted, steel bearing any content of carbon up to substantially .66% has been used, and, as a matter of fact, the best results have been obtained with the latter figure. Also I have found that when the carbon content of the steel is reduced to substantially .30%, the conductor is on the verge of losing the advantageous combination of electrical and mechanical properties, and when the carbon content is reduced still further, the object of my invention is substantially nullified.

The novel and useful results obtained by this invention embrace superior electrical and mechanical properties of the composite conductor combined with light protective coatings of the two principal metals employed. The kind of steel which is advantageously employed makes it possible to obtain a conductor which has very nearly constant effective resistivity to electrical currents such as are used in electrical power transmission, both with direct current and with alternating current, at the commercial frequencies in common use. Furthermore, the hard, tough steel which is used for giving the desired strength to the conductor also takes a superior quality of zinc coating as compared with those steels and irons which will not produce the results obtained by this invention.

By using steel having at least a .30% chemically combined carbon, and preferably more, the magnetic permeability under the internal magneto-motive-force created by the current in the conductor itself apparently is of insignificant magnitude. Also as the carbon content in the steel is increased not only does the magnetic permeability decrease, but also the "skin effect" decreases, as shown, for example, in Figure 7.

Referring to the diagram shown in Figure 7, it will be noted that there is shown a "skin effect" resistance increase in a copper-core steel strand three-eighths of an inch in diameter with a sixty-cycle alternating current

passing therethrough. Curve 14 shows the effect when a 10 ampere current is used; curve 15 when a 20 ampere current is used; curve 16 when a 30 ampere current is used; and curve 17 when a 40 ampere current is used. 70 Each curve shows that the "skin effect" is at its lowest value where the carbon content of the steel is above .66%, and that the "skin effect" gradually increases with a decrease in the carbon content of the steel, a critical point being reached at about .30% carbon content in the steel. As the carbon content of the steel is decreased from .30% the "skin effect" 75 greatly increases, showing that the object of my invention is nullified or defeated where steel is used in a composite electrical conductor in which the carbon content of the steel is less than .30%. 80

The invention is applicable to composite cables of various descriptions, as indicated 85 hereinabove; for example, in Figure 3, there is shown the core itself being stranded and comprising seven copper wires 18, there being two layers 19 and 20 of steel wires in a concentric-lay cable. 90

In Figure 4 a rope-lay cable is shown, in which there are seven main strands 21, 22, 23, 24, 25, 26, and 27 placed in concentric-lay, and each of these strands in turn consisting of seven wires in concentric-lay. The core strand 21 consists, for example, of seven wires of zinc-coated copper, and each of the six outer strands 22 to 27, inclusive, consists of six zinc-coated steel wires with a zinc-coated copper wire 28 in the center. 100

In Figure 5 another form is shown. In this instance a steel-covered copper wire is shown in which the copper core 29 preferably is brazed or welded to the surrounding steel element 30 and the latter is provided with a zinc coating 31. Such wire may be made into strands and cables in concentric-lay or in rope-lay, and in any other combination, as desired. 105

In Figure 6 a composite strand of cable 110 is shown in which the center wire 32 is copper provided with a zinc coating 33 and each of the outside wires is a composite conductor having a copper core 34 and a steel casing 35 with a zinc coating 36. 115

Steel of the proper carbon content, as indicated, when combined with copper in the various modifications shown, and in other modifications, provides a composite electrical conductor adapted to meet all of the requirements for the intended uses. 120

I define a composite electrical conductor as a conductor in which all of the constituent parts or elements are employed for conducting electrical current and which are in metallic contact with each other directly or indirectly. 125

In the claims when I refer to low magnetic permeability or low skin effect I mean a low magnetic permeability or a low skin effect 130

such as results when there is steel used or iron base material which has at least 30% chemically combined carbon.

I claim:

5. 1. A composite electrical conductor comprising two metals, one having the quality of relatively high electrical conductivity and the other being an iron-base metal of relatively great mechanical strength and containing at least as much as thirty hundredths per cent content of chemically combined carbon, said iron-base metal being so disposed in the body of the conductor that the metal of high conductivity is substantially enclosed thereby. 70
10. 2. A composite electrical conductor comprising two metals, one being copper for high electrical conductivity and the other being an iron-base metal of relatively great tensile strength and containing at least as much as thirty hundredths per cent content of chemically combined carbon for minimizing magnetic permeability, said copper being so disposed in the body of the conductor that it is substantially enveloped by the said iron-base metal. 80
15. 3. A composite electrical conductor comprising two metals, one having relatively high electrical conductivity and the other being steel containing substantially thirty hundredths per cent content or more of chemically combined carbon, said steel forming substantially the outer boundary of said conductor. 85
20. 4. A composite electrical conductor comprising two metals, one being copper for high electrical conductivity and the other being steel for high tensile strength and containing at least thirty hundredths per cent chemically combined carbon for substantially minimizing the electro-magnetic skin effect, said copper being so disposed in the body of the conductor that all the filaments of copper are substantially surrounded by filaments of the said steel. 90
25. 5. A composite electrical conductor composed of filaments comprising two metals, one kind being of relatively high electrical conductivity and the other kind being steel of relatively high tensile strength and relatively low magnetic permeability, said filaments being so disposed in the body of the conductor that the exterior surface of the conductor consists substantially of filaments of the said steel. 100
30. 6. A composite electrical conductor comprising two metals, one forming a non-ferrous core having high electrical conductivity and the other forming a ferrous covering of high tensile strength and relatively low magnetic permeability. 105
35. 7. A composite electrical conductor composed of two metals, one having the quality of high electrical conductivity and the other having an iron-base with the qualities of high strength and low magnetic permeability. 110
40. 8. A composite electrical conductor composed of two metals, one having the quality of high electrical conductivity and the other having the qualities of high strength and low magnetic permeability, the exterior of said conductor being comprised substantially of said metal of high strength and low permeability. 115
45. 9. A composite electrical conductor comprising two metals, one forming a core having the quality of good electrical conductivity and the other having an iron-base with the qualities of high strength and low magnetic permeability, the exterior of said conductor being comprised substantially of said metal of high strength and low permeability. 120
50. 10. A composite electrical conductor comprising two metals, one having the quality of good electrical conductivity and the other being steel and having relatively low magnetic permeability, every filament of the said metal of good electrical conductivity being substantially surrounded by filaments of the said steel. 125
55. 11. A composite electrical conductor comprising two metals, one forming a core having the quality of good electrical conductivity and the other forming a covering having an iron-base with the qualities of high strength and low magnetic permeability. 130
60. 12. A composite electrical conductor comprising two metals, one having the quality of good electrical conductivity and the other having an iron-base with the qualities of high strength and low magnetic permeability, the exterior of said conductor being comprised substantially of said metal of high strength and low permeability. 135
65. 13. A composite electrical conductor comprising two metals, one forming a core having the quality of good electrical conductivity and the other forming a covering having an iron-base with the qualities of high strength and low magnetic permeability, one of said metals having a coating of material to protect against corrosion. 140
70. 14. A composite electrical conductor comprising two metals, one forming a core having the quality of good electrical conductivity and the other forming a covering having an iron-base with the qualities of high strength and low magnetic permeability, both of said metals having coatings of material to protect them from corrosion. 145
75. 15. A composite electrical conductor com-

high tensile strength and relatively low magnetic permeability, the latter being so distributed in the conductor that the filaments of the metal of high electrical conductivity are substantially enclosed by it, one of said metals having a protective coating to delay corrosion. 70

80. 8. A composite electrical conductor composed of two metals, one having the quality of high electrical conductivity and the other having the qualities of high tensile strength and relatively low magnetic permeability, the latter being so distributed in the conductor that the filaments of the metal of high electrical conductivity are substantially enclosed by it, both of said metals having protective coatings to retard corrosion. 75

85. 9. A composite electrical conductor comprising two metals, one having the quality of relatively high electrical conductivity and the other having the qualities of relatively great strength and relatively low magnetic permeability and so disposed within the conductor and its filaments substantially enclose the filaments of the metal of high electrical 90 conductivity. 90

95. 10. A composite electrical conductor comprising two metals, one having the quality of good electrical conductivity and the other being steel and having relatively low magnetic permeability, every filament of the said metal of good electrical conductivity being substantially surrounded by filaments of the said steel. 105

100. 11. A composite electrical conductor comprising two metals, one forming a core having the quality of good electrical conductivity and the other forming a covering having an iron-base with the qualities of high strength and low magnetic permeability. 105

105. 12. A composite electrical conductor comprising two metals, one having the quality of good electrical conductivity and the other having an iron-base with the qualities of high strength and low magnetic permeability, the exterior of said conductor being comprised substantially of said metal of high strength and low permeability. 110

110. 13. A composite electrical conductor comprising two metals, one forming a core having the quality of good electrical conductivity and the other forming a covering having an iron-base with the qualities of high strength and low magnetic permeability, one of said metals having a coating of material to protect against corrosion. 115

115. 14. A composite electrical conductor comprising two metals, one forming a core having the quality of good electrical conductivity and the other forming a covering having an iron-base with the qualities of high strength and low magnetic permeability, both of said metals having coatings of material to protect them from corrosion. 120

120. 15. A composite electrical conductor com-

prising two metals, one having the quality of relatively high electrical conductivity and the other having an iron-base with the qualities of relatively great tensile strength and substantially minimum electrical skin-effect, substantially none of said metal of high conductivity being at the periphery of the conductor.

16. A composite electrical conductor comprising two metals, one forming a core hav-

ing the quality of good electrical conductivity and the other forming a ferrous covering of relatively great mechanical strength containing at least as much as thirty hundredths percent of chemically combined carbon for minimizing magnetic permeability.

Signed at Chicago, Illinois, this 28th day of June, 1924.

FRANK F. FOWLE.
